RAIL SANDING DEVICE

Frank E. Saari, Chicago, and Grant V. W.
Roth, Evanston, Ill.

Application June 26, 1946, Serial No. 679,450

2 Claims. (Cl. 291—11)

1

The invention relates to rail sanding devices. One object of the invention is to provide a sand trap for use on locomotives and delivering sand to the railway rails, which is simple in construction, efficient in operation, and includes an air jet for producing turbulence in the inlet leg of the casing of the track, close to and for siphonic action of, a second air jet which projects the sand directly into the pipe through which it is delivered onto the rails.

Heretofore, it has been proposed to use an air jet in the inlet branch of the trap which directs air into and agitates the sand in the dome, at a point remote from the Venturi formation between the inlet and outlet legs of the casing.

Another object of the invention is to provide a pocket formation in the inlet branch of the sand conduit and an air-jet which produces turbulence in the sand adjacent the Venturi opening and remotely from the end of the inlet leg which is closest to the sand dome. This pocket causes the air-jet to produce turbulence in the sand in close proximity to the Venturi formation and prevents the sand from becoming packed in the inlet leg without projecting air into the sand dome, so that the sand will be uniformly siphoned by the discharge jet which projects the sand into the delivery pipe.

Other objects of the invention will appear from the detailed description.

The invention consists of the several novel features hereinafter set forth and more particularly defined by claims at the conclusion hereof.

In the drawings:

Figure 1 is a longitudinal section of a sand trap embodying the invention.

Figure 2 is a section taken on line 2—2 of Figure 1.

Figure 3 is a section taken on line 3—3 of Figure 1.

Figure 4 is a section similar to Figure 2, illustrating a modified form of the invention.

The invention is exemplified in a sand trap which comprises a single casing generally designated 10, and is usually formed of cast metal. This casing includes at one of its ends a substantially horizontal leg or tubular extension 11, which is provided with a screw thread for communicative connection with the outlet on the sand dome from which the sand is supplied to the trap, and a downwardly inclined leg or tubular extension 12 at the opposite end, into which is screw threaded a pipe 13, for delivering sand from the trap to the rails.

The casing has a conduit for the sand which includes an inlet branch 14 in leg 11, a chamber 15 in the outlet leg 12, and a Venturi passage 18 between said inlet branch and said chamber. The casing is provided with oppositely disposed ledges or abutments 16, 17 between the inlet branch 14 and chamber 15 and in the bend

2

between said branch and chamber. Ledges 16 and 17 are convergent at one end of the inlet branch of the conduit and divergent in the outlet chamber 15, and form the Venturi opening 18. The top side 19 of inlet branch 14 in leg 11 is substantially straight from its inlet end to the ledge 16. The portion 20 of the lower side of branch 14 adjacent its inlet end is straight so that the portion formed by portion 18 and inlet portion is substantially cylindrical. In the remainder of the bottom side of the inlet-conduit between straight portion 20 and ledge 17, the casing is formed with a concave pocket 21, opposite the straight portion 19 adjacent the ledge 16.

15 A supply pipe 23 for compressed air is connected to one side of the casing 10 and communicates with a cylindrical chamber 24, which is provided with a tapered seat 25. A port 26 leads from the tapered seat 25. A screw 27 with a tapered inner end, is adapted to regulate the flow of air past the valve seat 25, to the port 26. A port 28 extends from the inner end of port 26, to deliver a jet of air into the inlet branch 14 of the sand conduit. The port 28 is disposed to direct the jet of air diametrically across the inlet branch of the sand conduit, near the center or deepest portion of the concave pocket 21. Concave pocket 21 is disposed adjacent the ledge 17 and opening 18, and the port 28 directs a jet 30 of compressed air across the sand conduit into said pocket. The concavity in the pocket causes the air-jet to swirl in the portion of the inlet-conduit adjacent the Venturi opening, and produce turbulence which loosens and displaces the sand in the pocket and prevents it from becoming packed during the operation of the sander. A plug 30 is screw threaded into casing 10, for access to and forming, port 28 in the casing. A port 29, substantially co-axial with the outlet chamber 15 and pipe 13, extends from port 26 to said chamber, and delivers a jet of air into said chamber for siphoning the sand from the inlet branch of the conduit adjacent pocket 21, through the Venturi opening and projecting it into the 40 delivery pipe 13.

45 The operation of the sander will be as follows: When the sander is inoperative the sand flows by gravity from the outlet of the sand dome into inlet 14 and concave pocket 21 and takes 50 substantially the position illustrated in Fig. 1 of the drawings. When compressed air is delivered into the air pipe 23, usually through an engineer's control valve, as well understood in the art, air will flow from seat 25, through ports 26 and 28, and deliver a jet of air across the inlet branch and into the concave pocket 21. Simultaneously, compressed air will flow from port 29, and deliver a jet of air through the outlet chamber 15, and into the delivery pipe 13. The air 55 jet from port 28 flows across the inlet conduit and strikes the sand inwardly of the lowest point 60

of the concave bottom of the pocket. The bottom of the pocket is curved upwardly from its point of greatest depth to the inlet 20 and to the ledge 17. The air from jet 28 strikes the sand in a zone between the point of greatest depth of the pocket and the inner end of inlet 20 where the air from jet 28 will deflect and loosen the portion of the sand on the bottom of the pocket, so that the sand will swirl upwardly from the lowest point of the pocket, and toward the opening 18. As a result the air will be deflected upwardly and away from inlet 20 and toward the Venturi opening 18, and during such deflection the sand will be loosened and caused to swirl in a zone where it will be siphoned through the opening 18. This produces turbulence in and loosens the sand in the pocket immediately adjacent the ledges 16 and 17 and Venturi opening 18, which prevents the sand from becoming packed or accumulating in the pocket 21 and in said opening during the operation of the sander. The jet of air from port 29, will siphon the turbulent and loose sand through the Venturi opening and forcibly project the sand into the delivery pipe. In this operation, the swirling air will be substantially confined to the portion of the inlet duct adjacent the Venturi passage, and will not retard the flow of sand from the sand dome into the inlet conduit. It will be observed that the jet of air from port 28 is directed downwardly across the sand conduit to a portion of the pocket 21, which will deflect the air toward the ledge 17 and to the Venturi opening 18. As a result, the preponderance of turbulent and loose sand will be deflected away from the inlet end of conduit 14 and toward the Venturi opening. As the sand is discharged from the lower portion of the pocket 21 by the air jet from port 28, the sand from inlet 20 will flow into the lower portion of pocket 21 to replace the sand discharged.

As a result of this construction, the sand for projection into the delivery pipe will be siphoned from the sand in a state of turbulence produced by the jet of air across the inlet conduit at the pocket 21, with the result that the delivery of the sand will be constant and uniform, and the flow of sand from the dome will not be retarded.

In the modification of the invention illustrated in Fig. 3, the port for delivering a jet of air from port 26, is connected to an oblique port 28a, which delivers the air tangentially into the inlet conduit and the concave pocket 21, to cause the air to swirl around the periphery of the pocket and produce turbulence of the sand therein. In the construction illustrated in Figs. 1 and 2, the port 28 delivers the jet of air transversely across the inlet conduit, so that the stream of air will be divided and directed tangentially around the periphery of the pocket and inlet conduit adjacent the Venturi opening.

The invention exemplifies a sand trap which is provided with a pocket in the inlet branch of the sand conduit and adjacent the Venturi opening for co-acting with a supplemental jet of air to produce a turbulence or swirling of the sand at a point close to the jet of air for discharging the sand through the outlet leg of the casing, and without directing the air into the sand dome where it will retard the sand, and whereby the accumulation or packing of the sand adjacent the Venturi opening will be prevented and the sand will be discharged at a pre-determined rate, into the delivery pipe, by the second air jet.

The invention is not to be understood as limited to the details described, since these may be modified within the scope of the appended claims without departing from the spirit or scope of the invention.

Having thus described the invention, what we claim as new and desire to secure by Letters Patent is:

1. A trap for sanding rails comprising: a casing including a substantially horizontal inlet leg provided with means for connecting to the side of a sand dome, a downwardly inclined outlet leg provided with an outlet chamber, a downwardly inclined delivery pipe leading from said outlet chamber, the inlet leg having a sanding conduit with a substantially horizontal portion extending inwardly from its outer end, upper and lower ledges forming a Venturi opening between the outlet chamber and said conduit, the casing being provided with a concave pocket extending below and merging onto the inner end of the bottom of the horizontal portion of the conduit, and merging upwardly into the lower ledge, the top of the horizontal portion of the conduit merging downwardly into the upper ledge, means for delivering a jet of air under pressure from the top of and across said conduit, and directing it to a portion of the pocket which is curved to deflect sand toward the Venturi opening and away from the inner end of the bottom of the horizontal portion of the conduit, and means for delivering a jet of air into the outlet chamber for projecting the sand from the outlet chamber through the discharge pipe.
2. A trap for sanding rails comprising: a casing including a substantially horizontal inlet leg provided with means for connecting to the side of a sand dome, a downwardly inclined outlet leg provided with an outlet chamber, a downwardly inclined delivery pipe leading from said outlet chamber, the inlet leg having a sanding conduit with a substantially horizontal portion extending inwardly from its outer end, upper and lower ledges forming a Venturi opening between the outlet chamber and said conduit, the casing being provided with a concave pocket extending below and merging into the inner end of the bottom of the horizontal portion of the conduit, and merging upwardly into the lower ledge, the top of the horizontal portion of the conduit merging downwardly into the upper ledge, means for delivering a jet of air under pressure from the top of and across said conduit, and directing it downwardly and tangentially to one side of a portion of the pocket which is curved to deflect the sand toward the Venturi opening and away from the inner end of the bottom of the horizontal portion of the conduit, and means for delivering a jet of air into the outlet chamber for projecting the sand from the outlet chamber through the discharge pipe.
